HIGH VOLTAGE INSULATOR MOUNTING BRACKET

Charles Don Snodgrass, Orinda, Calif., assignor to
Kearney-National, Inc., a corporation of Delaware

Filed Dec. 15, 1967, Ser. No. 9,799

Term of patent 14 years

(Cl. D26—9)

FIGURE 1 is a side view of the insulator mounting of the present invention;

FIGURE 2 is an underside view of the insulator mounting of FIGURE 1; and

FIGURE 3 is a front end view of the same.

The broken line disclosure of an insulator in FIGS. 1 and 2 is for illustrative purposes only.

I claim:

The ornamental design for a high voltage insulator mounting bracket, as illustrated and described.
